UNITED STATES PATENT OFFICE

JOSEPH D. WOOD, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

THERMORESPONSIVE APPARATUS

Application filed July 1, 1927. Serial No. 202,949.

This invention relates to electrically actuated thermo-responsive devices especially adapted to effect the opening of an electric switch upon overload in the switch circuit, although not necessarily restricted to such use.

An object of the invention is the provision of a thermo-responsive device as a unitary piece of apparatus adapted for many different purposes.

A further object is the provision of a thermo-responsive apparatus having a spring tensioned actuating member with means governed by the thermo-responsive elements to hold said member in set condition and to release it for movement under the action of its spring to effect the tripping of the switch or the control of some suitable circuit or device, combined with means to effect the manual resetting of the actuating member after it has been operated.

A further object of the invention is a novel form of thermo-responsive apparatus having a spring tensioned actuating member normally held in set position in readiness for operation and a plurality of thermo-responsive elements each adapted independently and all conjointly to effect the release of the actuating element for operation.

A further object is generally to improve the construction and operation of electrically actuated thermo-responsive apparatus.

The device embodying this invention is described in my co-pending application Serial No. 202,950 filed—July 1, 1927.

Fig. 1 is a side elevation of the thermo-responsive apparatus embodying the invention.

Fig. 2 is an end view of the apparatus of Fig. 1.

Fig. 3 is a perspective view of the tripping frame.

Fig. 4 is an end view partly in section of one of the thermo-responsive devices.

Fig. 5 is a longitudinal sectional view taken along line 5—5 of Fig. 4.

Fig. 6 is a section taken along line 6—6 of Fig. 5.

Fig. 7 is a view of the connecting strip ex-

tended between the holding frame and the thermo-responsive devices.

Fig. 8 is a section diagram illustrating the manner in which a thermo-responsive device can be connected in an electric circuit.

The thermo-responsive apparatus embodying this invention comprises a supporting frame having the spaced integral upstanding side walls 10 and 12 and the bottom connecting wall 14. A tripping frame comprising a pair of closely spaced plates 16 and 18 is pivotally mounted on a bolt 20 extended between and carried by the upper portions of the side walls. Said plates 16 and 18 are riveted together at appropriate points and are provided with flat upper faces 22 which are adapted to strike against the latch 24 of a switch 26 to effect the opening of the switch; or to actuate some other appropriate mechanism. A tensile spring 28 is disposed between said plates 16 and 18 and has its upper end connected with a pin 30 of the tripping frame and its lower end connected with a pin 32 carried by the side walls 10 and 12 in the lower portion thereof. Said spring is disposed at one side of the pivotal center of the tripping frame and so biases the frame for rotation in a counter-clockwise direction as viewed in Fig. 1.

The frame is normally held in the set position illustrated in Fig. 1 by a holding frame 36 which has spaced side walls 38 pivoted on the pin 32 and upstanding ears 40 between which a roller 42 is journaled. Said roller is adapted to overlie a roller 44 carried between the plates 16 and 18 of the tripping frame to hold the tripping frame in set position. A compression spring 46 is disposed under the holding frame and serves normally to hold it in the elevated position shown in Fig. 1, and in engagement with the tripping frame.

When the tripping frame is released, it is adapted to move upward under the action of the tensile spring 28 and is adapted to remain in elevated position until reset. The frame is adapted to be reset by a resetting pin 48 which may be manually operated and which works in an arcuate slot 50 in the side

wall 10 of the supporting frame and is adapted to engage a depending ear 52 of the plate 16 of the tripping frame, thus to move it in a clockwise direction into re-engagement 5 with the holding frame.

The holding frame is adapted to be moved downwardly by thermo-responsive devices carried by the wall 12 of the supporting frame and illustrated more specifically in 10 Figs. 4 and 5. The thermo-responsive devices are identical and but one needs to be described. Each device is carried by a bracket 53 having spaced ears 54 at the end provided with slots 56 in which the thermo- 15 responsive elements are received. A screw 58 having an enlarged head 60 is received in one of the ears 54 and an insulating bushing 62 is received in the other ear. A screw 64 is extended through said bushing co-axially with 20 the screw 58 and is held in location by the nut 66. A heater element comprising a spiral coil 68 of suitable resistance material is extended between and is secured electrically to the screws. A cylindrical metal tube 70 25 surrounds the heating element and is rotatable on the enlarged head 60 of the screw 58 and upon the head of the bushing 62. A spiral thermo-responsive member 72 of tubular or helical formation formed of a strip of ther- 30 mostatic metal composed of two metals having dissimilar expansion co-efficients, as copper and iron fixedly united together, is received within the tube 70 and has one end thereof fixed to the tube by the rivet 74. The other and free end 76 is extended freely 35 through an opening 77 in the side of the tube and has an outwardly projecting tongue 78. The supporting brackets for the thermo- 40 responsive elements are secured one above the other to the side wall 12 of the supporting frame and the tongues 78 are received in vertically elongated slots 80 of a vertical connecting member 82, the lower end of which is connected loosely with a pin 84 carried by 45 the holding frame 36.

The heater elements are adapted to be heated by current from some appropriate source as a current set up in the secondary winding of a current transformer 83, Fig. 8, 50 which is included in series with the circuit 85 of the switch 26. As thus arranged, the spiral thermostatic elements 72 are adapted to expand when sufficiently heated and to move the free ends 76 thereof downwardly, 55 thus moving the holding frame 36 downwardly against the action of the spring 46 and releasing the tripping frame 16 which is thus free to move upwardly and trip the switch open. The time and current settings 60 of the thermo-responsive elements can be varied by rotating the tubes 70 and thus altering the positions of the free ends of the thermostatic elements in the slots of the connecting strip 82. For this purpose plates 86 are secured to said tubes at similar ends thereof 65

and are pivotally connected with a vertical adjusting rod 88, the upper end of which extends through an ear 90 of the side wall 12 of the supporting bracket and has a screw threaded nut 92 thereon. It is apparent that 70 by rotating the nut 92, the rod 88 may be raised and lowered, thus to rotate the tubes 70 about their axes and change the adjustment of the thermo-responsive elements.

Preferably the thermostatic element 72 75 is arranged close to the inner face of the tube 70 with the material of least expansion outermost. Thus, in Fig. 6, the copper section 72a of the thermostatic element is innermost and the iron section 72b outermost. This arrangement, combined with the heat absorbing and dissipating characteristics of the metal tube 70, provides a device which is sensitive to sudden overloads so that it can trip the switch open rapidly without the usual 80 long delay provided by devices of this character. It will be apparent that upon sudden heating of the heating element, the copper section of the expansible element 72 will become heated and will expand while the iron section will be kept cool by its proximity to the metal enclosing tube 70 so that quick expansion of the device will result. On lower or more gradually applied overloads, the two 85 metals of the spiral thermostatic element will 90 heat more or less uniformly, however.

While I have shown my device associated with an electric switch for purposes of illustration, the device can be used for other purposes with little or no modification as will be 100 apparent.

I claim:

1. In a thermo-responsive apparatus, the combination of a movable holding member, a plurality of thermo-responsive devices having means whereby they can be initially set to operate in accordance with any one of a plurality of predetermined conditions, means connecting said devices with said holding member by which all thermo-responsive devices 105 conjointly and also each thermo-responsive device independently of the others can actuate said holding member, and means for simultaneously varying the settings of 110 said thermo-responsive devices. 115

2. In a thermo-responsive apparatus, the combination of a plurality of thermo-responsive members having independent and fixed supports on which they are separately adjustable, actuating means controlled by said 120 members singly and also in unison, and means to effect the simultaneous adjustment of all said members on their several supports in the same direction.

3. In a thermo-responsive apparatus, the combination of a plurality of separately-acting adjustable thermo-responsive members which are responsive to different conditions having individual adjustment elements, means separately and also conjointly con- 125 130 135

- trolled by said members, and means to effect the simultaneous adjustment of said members relatively to said controlled means including an adjustment-member having connections with said adjusting elements of all said thermo-responsive members by which said thermo-responsive members can act separately and also conjointly on said controlled means. 5
4. In a thermo-responsive device, the combination of a thermally expansible member having a free end, a fixed end, a rotatable support for the fixed end and a fixedly supported heating element for said expansible member extended lengthwise thereof and located within said rotatable support. 10
5. In a thermo-responsive device, a thermally expansible element of helical formation having a fixed end and a free end, means to vary the setting of said expansible element including means to rotate said element, and a fixedly supported heating element extended through said rotatable expansible element. 15
6. In a thermo-responsive device, a thermally expansible element of helical formation having a fixed end and a free end, a rotatable support for the fixed end generally coaxially disposed with the axis of said helical element, and a heating element having fixed supporting means therefor extended through said helical element. 20
7. In a thermo-responsive device, a thermally expansible element, an enclosing tube surrounding said element, said element having one end fixed to said tube and a free end extended outwardly through a wall of said tube intermediate its ends, said tube characterized by being rotatable about its axis, means to hold said tube in any rotated position thereof, and an electric heating element extended through said tube and said expansible element. 25
8. In a thermo-responsive device, a thermally expansible element of helical formation, an enclosing tube surrounding said element, said element having one end fixed to said tube and a free end extended outwardly of said tube, said tube characterized by being rotatable about its axis, means to hold said tube in any rotated position thereof, and an electric heating element extended through said tube and said expansible element. 30
9. In a thermo-responsive device, a tube of substantial length, supports for the ends of said tube on which said tube is rotatable, a thermally expansible element of generally helical formation disposed within said tube and having one end thereof fixed thereto and having the other end freely extended outwardly of said tube, and a heating member to heat said expansible helical element located therein. 35
10. In a thermo-responsive device, a supporting bracket having a pair of spaced co-
- axial shoulders, a cylindrical tube having its open ends encircling and journalled upon said shoulders, and a thermally expansible element of helical formation received within said tube having one end fixed to said tube intermediate its ends, and means to hold said tube against rotation on its journals in any one of a plurality of angularly related positions and having its other end freely extended outwardly of said tube. 40
11. In a thermo-responsive device, the combination of a rotatably supported tube, an electric heating element located within said tube, a thermally expansible element disposed alongside said heating element within and rotatable with and having one end fixed to said tube and having a radially-extended free end, means operated by said free end, and means to fix said tube against rotation on its support in any one of a plurality of 45 positions. 45
12. In a thermo-responsive device, the combination of a supporting bracket, a screw having an enlarged cylindrical head carried by said bracket at one end, an insulating bushing carried by said bracket at the other end, a tube loosely received on said bushing and the head of said screw and rotatable on both, a thermally expansible element received within said tube and having one end fixed to said tube and having its other end extended freely outwardly of said tube, and a heating element extended within said tube adjacent said expansible element having one end thereof connected electrically with said screw and having an electrical connection at its other end extended through said bushing. 50
13. In a thermo-responsive device the combination of a cylindrical heat-absorbing metal tube, a generally cylindrical thermally expansible member composed of two sections having different coefficients of expansion received within said tube and having its most expansible section innermost and its least expansible section closely adjacent and in heat-transferring relation with said metal tube and a heater element disposed within said tube adjacent said most expansible section. 55
14. In a thermo-responsive device, the combination of a U-shaped supporting frame having spaced upstanding side walls, a pivotally supported tripping frame disposed adjacent one of said side walls, a spring urging said frame for rotation about its pivot, a holding frame disposed beneath said tripping frame and normally engageable therewith to hold it from engagement, and a thermo-responsive device carried by the other wall of said supporting frame at one side of said holding frame having an operative connection with said holding frame and arranged to move it to release said tripping frame. 60
15. In a thermo-responsive device, a bracket having spaced parallel arms, 65

- aligned confronting cylindrical supports carried by said arms, one of which supports is connected electrically with and the other is insulated from said bracket, a tube extended between said arms and rotatable on said supports, a helical thermo-expansible member located within said tube and having one end fixed thereto and the other end extended freely laterally through an opening 5 in the side wall of said tube, and a heating member extended through said helical member having one end connected to said electrically-connected support and its other end extended through said insulated support.
16. A thermo-responsive device having the combination of a tripping frame, a spring urging said frame for movement into an operated position, a holding frame normally holding said tripping frame in an 10 inoperated position against the action of said spring, a plurality of thermally-expansive members each having a fixed end and a movable free end, said free ends having independent lost-motion connections with said holding frame by which each thermally-expansive member independently can operate said holding frame, and adjusting means connected with all of the fixed ends of said thermally-expansible members are arranged 15 to move said ends in unison.
17. A thermo-responsive device having the combination of a supporting frame having an upstanding wall, a tripping frame having a pivotal support on said supporting frame and located on one side of said wall, a spring urging said tripping frame for movement to an operated position, a holding frame having a pivotal support on said supporting frame and located on the same 20 side of said wall with said tripping frame and arranged to hold said tripping frame normally in an unoperated position, thermo-responsive means to depress said holding frame and to move it out of holding relation with said tripping frame, and a resetting member located mainly on the side of said wall opposite said tripping frame having an extension which is extended through an opening in said wall and is normally free 25 from said tripping frame and is movable into engagement therewith in a direction to return it to the engagement of said holding frame.
18. A thermo-responsive device having the combination of a U-shaped supporting frame, a tripping frame comprising a pair of spaced plates having a pivotal connection with said supporting frame, a roller journalled between said plates, a spring en- 30 gaging said tripping frame urging it toward an operated position, a holding frame comprising a pair of spaced L-shaped members having a pivotal connection at one end with said supporting frame and having a 35 roller located between the other ends there- of which normally engages said roller of said tripping frame, means to hold said holding frame removably in the aforesaid relation, and a thermo-expansible member carried by said supporting frame beside 40 said holding frame and having an operative connection therewith and arranged to move said holding frame from holding engagement with said tripping frame.
- In testimony whereof, I have signed my 45 name to this specification.

CERTIFICATE OF CORRECTION.

Patent No. 1,872,208.

August 16, 1932.

JOSEPH D. WOOD.

It is hereby certified that error appears in the printed specification of the above numbered patent requiring correction as follows: Page 3, line 71, claim 10, beginning with the word "intermediate" strike out all to and including the word "positions" in line 74, and line 75, same claim, after the word "tube" insert the words intermediate its ends, and means to hold said tube against rotation on its journals in any one of a plurality of angularly related positions; and that the said Letters Patent should be read with this correction therein that the same may conform to the record of the case in the Patent Office.

Signed and sealed this 22nd day of November, A. D. 1932.

(Seal)

M. J. Moore,
Acting Commissioner of Patents.
